UNITED STATES PATENT OFFICE

140,901

DESIGN FOR A CABINET TYPE REFRIGERATOR AND KITCHEN UNIT

John H. Benson, Salem, Ohio, assignor to Mullins Manufacturing Corporation, Salem, Ohio, a corporation of New York

Application November 17, 1944, Serial No. 116,409

Term of patent 7 years

(Cl. D67—3)

To all whom it may concern:

Be it known that I, John H. Benson, a citizen of the United States, residing at Salem, in the county of Columbiana and State of Ohio, have invented a new, original, and ornamental Design for a Cabinet Type Refrigerator and Kitchen Unit, of which the following is a specification, reference being had to the accompanying drawing, forming part thereof.

The drawing illustrates a perspective view of the top, front and one end of the cabinet type refrigerator and kitchen unit. The other end of the cabinet (not shown) is the same as the end illustrated. The back of the cabinet is plain.

I claim:

The ornamental design for a cabinet type refrigerator and kitchen unit, substantially as shown and described.

JOHN H. BENSON.
